UNITED STATES PATENT OFFICE.

HERBERT H. DOW, OF MIDLAND, MICHIGAN, ASSIGNOR TO THE DOW CHEMICAL COMPANY, OF MIDLAND, MICHIGAN, A CORPORATION OF MICHIGAN.

RECOVERY OF COAL-DISTILLATION PRODUCTS.

1,317,359.

Specification of Letters Patent. Patented Sept. 30, 1919.

No Drawing.

Application filed January 14, 1918. Serial No. 211,726.

To all whom it may concern:

Be it known that I, HERBERT H. Dow, a citizen of the United States, and a resident of Midland, county of Midland, and State 5 of Michigan, have invented a new and useful Improvement in the Recovery of Coal-Distillation Products, of which the following is a specification, the principle of the invention being herein explained and the 10 best mode in which I have contemplated applying that principle, so as to distinguish it from other inventions.

In the destructive distillation of coal, one of the main fractions of the by-products 15 recovered from the distillation process is the so-called first light oil, which is the fraction distilling at a temperature up to 170 degrees centigrade. This fraction is made up of benzene, toluene and higher homologues, with phenol, cresol, naphthalene, etc. The products obtained from it are then 20 separated by redistilling the whole fraction in a small still of the same general type as the large tar still from which the main fraction is derived. By this redistillation such 25 first light oil is ordinarily separated into three sub-fractions, the first of which constitutes the so-called "90% benzol" which is the product coming over at temperatures up to 110 degrees centigrade. The actual 30 percentage composition of the 90% benzol of good quality is about 70% benzene, 24% toluene, including a little xylene, and 4 to 6% of carbon bisulfid and light hydro- 35 carbons.

The present improved process is more particularly concerned with the treatment of such carbon bisulfid and light hydrocarbons, these heretofore having been found inseparable 40 because of their having approximately the same boiling point, and so far as I am aware, no method has heretofore been practised for making any economical use of such products, despite their obviously valuable character, particularly that of carbon bisulfid.

With this object in view, the present invention then consists of the steps herein-after fully described and particularly 50 pointed out in the claims, it being understood that the following description discloses only one of various ways in which the principle of the invention may be carried out.

55 As indicated above, the principal light

hydrocarbon which remains associated with the carbon bisulfid after the redistillation of the high fractions of the benzol, I have found is pentane (C_5H_{12}), which has a boiling point of from 37 to 39 degs. centigrade. The boiling point of carbon bisulfid being around 46 degs. centigrade, it will be seen that the separation of these two constituents by the ordinary process of fractional distillation would be a very tedious 60 one if possible at all.

I have discovered, however, that it is perfectly feasible to convert this light hydrocarbon into a substitution product having a very considerably higher boiling point 70 than carbon bisulfid, by treating the mixture with a halogen, *i. e.*, chlorin or bromin, or both, in the presence of a suitable catalytic agent such as iron. The result of such treatment where chlorin is used is presumably the formation of pentyl chlorid ($C_5H_{11}Cl$), at least in part, which has a boiling point of approximately 160 degs. centigrade. 75

Such treatment with chlorin or bromin, 80 however, does not affect in any way the carbon bisulfid (CS_2) so that such bisulfid may be readily separated from the resulting mixture of the bisulfid with the halogenated pentane or other light hydrocarbon, by the 85 familiar process of fractional distillation. In this way, not only is the valuable carbon bisulfid segregated by the halogenated hydrocarbon likewise constitutes a valuable product, being available for various uses 90 in the arts.

Other modes of applying the principle of my invention may be employed instead of the one explained, change being made as regards the process herein disclosed, provided the step or steps stated by any one of the following claims or the equivalent of such stated step or steps be employed. 95

I therefore particularly point out and distinctly claim as my invention:— 100

1. In the recovery of coal-distillation products, the steps which consist in segregating the fraction which contains pentane and carbon bisulfid, these constituents having approximately the same boiling point, and 105 then treating such fraction with a halogen, whereby such pentane is converted into a product having a higher boiling point than, and so separable from, such carbon bisulfid.
2. In the recovery of coal-distillation 110

- products, the steps which consist in segregating the fraction which contains pentane and carbon bisulfid, these constituents having approximately the same boiling point, 5 and then treating such fraction with a halogen in the presence of a catalyst capable of inducing reaction between the same, whereby such pentane is converted into a product having a higher boiling point than, and so 10 separable from, such carbon bisulfid.
3. In the recovery of coal-distillation products, the steps which consist in segregating from the first light oil the sub-fraction which contains pentane and carbon bi- 15 sulfid, these constituents having approximately the same boiling point, and then chlorinating such pentane, whereby it is converted into a product having a higher boiling point than, and so separable from, such 20 carbon bisulfid.
4. In the recovery of coal-distillation products, the steps which consist in segregating from the first light oil the sub-fraction which contains pentane and carbon bi- 25 sulfid, these constituents having approximately the same boiling point, and then treating such pentane with chlorin in the

presence of iron, whereby it is converted into a product having a higher boiling point than, and so separable from, such carbon 30 bisulfid.

5. In the recovery of coal-distillation products, the steps which consist in segregating from the first light oil the sub-fraction which contains pentane and carbon bisulfid, 35 these constituents having approximately the same boiling point, and then halogenating such pentane, whereby it is converted into a product having a higher boiling point than, and so separable from, such carbon 40 bisulfid.

6. In the recovery of coal-distillation products, the steps which consist in segregating from the first light oil the sub-fraction which contains pentane and carbon bisulfid, 45 these constituents having approximately the same boiling point, and then converting such pentane into a product having a different boiling point than, and so separable from, such carbon bisulfid. 50

Signed by me this 9th day of January, 1918.

HERBERT H. DOW.
